GARMENT CONDITIONING APPARATUS
August F. Paris, 1025 Oak St., Brockway, Pa.
Filed June 30, 1961, Ser. No. 121,235
8 Claims. (Cl. 223—70)

This invention relates to garment finishing apparatus for use in the pressing, shaping, and otherwise conditioning garments for wear both before and after they have been worn.

An object of the invention is to produce improved apparatus the function of which is similar to that of the apparatus disclosed in my United States Patent No. 2,915,229 of Dec. 1, 1959, for steaming and conditioning garments.

A further object of the invention is to produce apparatus and procedure for subjecting every portion of the fabric of a garment being processed to a flow of high temperature steam to thereby renovate the entire garment during a single operation and an operation which may be controlled by a single operator.

A further object of the invention is to produce apparatus for thoroughly conditioning garments for wear while, at the same time, avoiding the possibility of water-spotting the fabric of the garment being processed by subjecting it to contact with prematurely formed water of condensation or water from any source.

These and other objects, which will be made apparent throughout the further description of the invention, are attained by the use of apparatus disclosed in the accompanying drawings and in the procedure herein outlined in connection with that apparatus.

FIGURE 1 is a vertical sectional view of apparatus embodying my invention shown in connection with a diagrammatic fragmental sectional view of a permeable bag such as a fabric bag to be employed in connection with apparatus embodying my invention;

FIGURE 2 is a plan view of a portion of the apparatus shown in FIGURE 1, the view is taken as from the line II—II of FIGURE 1;

FIGURE 3 is a fragmental vertical sectional view of the apparatus shown in FIGURE 2, the section being taken along the line III—III of FIGURE 2;

FIGURE 4 is a sectional view of the apparatus shown in FIGURE 1, the section being taken on line IV—IV of FIGURE 1;

FIGURE 5 is a sectional view of a portion of the apparatus shown in FIGURES 1 to 3, the section being taken along the line V—V of FIGURE 1; and

FIGURE 6 is a schematic view of the apparatus embodying my invention which is shown in connection with arrows indicating the flow of steam to and through the apparatus.

The apparatus here disclosed includes in its make-up a base 7, an upwardly extending open top, annular wall or casing member 8 mounted on the base 7, a system of heating coils or conduit means 11 located above the base and surrounded by the annular wall 8, a steamer 12 mounted on wall 8, a motor-driven fan 10 for propelling a stream of air through the wall 8, over the system of heating coils 11, past the steamer 12 and into a garment being processed, i.e., a garment (not shown) which is suspended above the annular wall 8 with its bottom portion surrounding the steamer and preferably secured to the upper portion of the wall 8, so that the stream of air propelled by the fan moves into such garment. The arrangement of the illustrated apparatus is such that the air delivered by the fan picks up steam delivered by the steamer and the mixture of steam and air passes through substantially every portion of the fabric included in the

2

make-up of the garment suspended above the annular wall 8 and steamer 12.

A transversely perforated steamer block 13 forms an essential part of a so-called steamer 12 which is supported by the wall 8 and is located above and substantially centrally of the heating coils 11 and the fan 10. A plurality of transversely extending passages 14 are formed in the block 13 for delivery of upwardly directed jets of steam into the stream of air propelled by the fan and moving into the interior of such garment as is suspended above the steamer 12 and is also secured to the wall 8.

A feature of the present invention is that the steamer block 13 is separately heated to a temperature substantially above that of the steam normally delivered in the form of jets from formerly employed steamers. The steam enters the passages 14 at the lower end of the block, where each passage 14 is of substantial cross sectional area, and then exits from the top of the block where the passages 14 are of reduced cross section area. This will, in effect, increase the density of the steam as it passes through the passages of the block 13 and, in effect, super-heat the steam as it passes through the passages 14 of the heated block where it is then emitted with increased velocity. Thus the steam is raised to a super-heat temperature as a preliminary to passing it through the fabric of the garment on and surrounding the form.

Another feature of the invention is that each fluid passage 14 formed in the block 13 and extending transversely therethrough, is of substantial length (about 1½ inches long) and, at its exit end, is less than half its cross sectional area at its entrance end. Consequently, the steam entering each passage 14 is not only checked in its flow through the block 13, but is also forced into intimate contact with the heated walls of the passages 14 in the highly and separately heated block 13. This arrangement of apparatus and procedure is highly effective in increasing the temperature of the steam as it passes through the block with the results that the steam issuing as jets from the steamer is not only dry but is also super-heated steam.

40 In the apparatus illustrated, the base 7 is circular and the wall 8 is secured to an upwardly projecting annular leg of an angle bar 7a forming a part of the base. The upper end of the wall 8 is secured to an annular member 15 which in turn supports cross members (not shown) 45 on which the steamer 12 is mounted. The lower portion 8a of the wall 8 may be, and preferably is formed of screening and the heating coils 11 heat the air drawn into the cylindrical wall 8 by the fan 10, to a relatively high temperature. The fan is similar to the fan disclosed in 50 said Patent No. 2,915,229, and, as indicated, is driven by motor 16.

The steamer 12 includes a body member 12a that forms a chamber 17 which partially surrounds a central support member 18. A portion of chamber 17 is arc-shaped and 55 is closed at its upper end by the steamer block 13. As shown, chamber 17 receives steam from the supply line 19 which receives steam from a high pressure source through a valve 19a. As is usual procedure, steam is periodically delivered to the chamber 17. This is accomplished in the illustrated embodiment of the invention by an automatically controlled solenoid valve 19b. As shown 60 in FIGURE 1, the supply line 19 delivers into a special T fitting 19c and the solenoid valve 19b is located in a side line or first branch conduit like 19d which communicates with the side exit of the T fitting 19c and also communicates with the interior of the chamber 17 of the steamer at a point well above the bottom of the chamber. The continuation of the supply line 19 is shown as 65 70 a pipe 22 of reduced area which delivers steam from the main discharge port of the T fitting 19c into a heating passage 22a of the steamer block 13, which passage is

disclosed in FIGURE 2 and will hereinafter be more fully described.

The steamer block 13 is mounted on and secured to the vertical wall of the steamer 12 and all of the passages 14, formed in the block, receive steam from the chamber 17. As stated and as shown in FIGURES 1 and 3, the lower portion of each passage 14 is of substantially larger diameter than the upper portion thereof. In the apparatus here described, the lower portion of each aperture 14 is $\frac{1}{8}$ inch in diameter, whereas, the upper portion is less than $\frac{1}{16}$ inch in diameter.

The steamer block 13 is provided with an interior heating passage 21 which, as shown in FIGURE 2, is made up of four communicating drilled passages to which high pressure steam is delivered through a pipe or second branch conduit 22 and from which the steam is delivered through a delivery pipe 23-24. As shown in FIGURE 1 and as indicated in FIGURE 6, the pipe 23-24 communicates with a passage 25 (FIGURE 1), formed in the shell of the steamer and which communicates at its inner end with a chamber 26 formed in the support member 18 forming a part of the steamer.

As shown in FIGURES 1 and 6, steam entering the steamer chamber 26 is delivered by piping 27 to the system of coils 11 and, after passing through those coils, the steam and such condensation as is carried by the steam is discharged through the outlet 28. As shown in FIGURE 1, the outlet 28 communicates with a steam trap 28a. The trap is such that it will discharge the condensate but will retain the steam under high pressure in all three of the heating units, viz., the coils 11, the block 13, and the chamber 26.

From the foregoing it is apparent that the steamer block 13 receives a flow of heating fluid (preferably steam) through the pipe 22 and that heating steam is delivered to the coils 11 by the chamber 26 of the steamer and the piping 23-24 and the pipe 27. Thus, the steamer block is continuously heated preferably to a temperature within the range of from 220° to 290° F. and the flow of air delivered by the fan 10 to the interior of the bag 20 is likewise preferably heated to a temperature within that range as it is mixed with the steam delivered by the passages 14 of the steamer block 13.

The block 13 is formed of heat-conducting material, preferably metal, consequently, both the steam and the air are delivered into the permeable bag 20 at a temperature such as to normally prevent the formation of water of condensation. It is stressed that the steam entering the passages 14 of the block 13 is checked in its flow through those passages by the reduction in the area of the exit end of each such passage. This results in a correspondingly greater density of the steam moving through the passages 14 and this causes a build-up of the velocity of the flow emitting from each of those passages.

Such condensate as is carried by the steam entering the steamer chamber 17, drops to the bottom of that chamber and is continuously evaporated by the heat delivered to the chamber 26 of the steamer. It should be noted that the body of steamer block 13, which is of a material having a high coefficient of heat conduction, is maintained at a consistent temperature which is higher than the temperature of the steam entering chamber 17. The higher temperature of steamer block 13 is achieved through the maintenance of a flow of pressurized steam moving through conduit 21, wherein the friction of the continual flow upon the inner walls of conduit 21 causes the conversion of kinetic energy to heat energy which is transferred to steamer block 13 and subsequently to the steam flow within apertures 14 by thermal conductivity. It is also noted that such particles of water condensation as may be picked up by the steam leaving the chamber 17 and entering the passages 14 of the steamer block 13, receive heat from the heated block 13 and are raised to a temperature such that they immediately evaporate into relatively high pressure steam as they issue with the steam

jets from the passages 14 of the steamer. From this it is apparent that the arrangement of the steam passages 19 and 19d with relation to the chamber 17 is such that the steamer acts as the steam separator and that under normal operating conditions the steam delivered from the chamber 17 to the passages 14 of the highly heated steamer block 13 is dry steam devoid of moisture. In any event, the steam leaving the steamer block 13 and entering the substantially atmospheric pressure within the bag 20, in effect, explodes with the result that any particles of moisture carried by the super-heated steam are expanded into hot spray or steam existing at a temperature substantially above condensation temperature. As a result, steam issuing from the permeable bag 20 and passing through the fabric of the garment being processed will uniformly dampen the fabric of the garment but only enough to make the fabric pliable and thus remove such wrinkles as may have been formed in it.

It is apparent that the steamer block 13 may be made in various sizes and, therefore, can be installed over, or in connection with various chambers from which steam is delivered into garments for the purpose of moistening the fabric of the garments.

In FIGURE 2 of the accompanying drawings I have disclosed the inlet passage 22 as provided with an interiorly threaded inlet aperture 22a. I have also shown the outlet passage 23 provided with an interiorly threaded outlet aperture 23a. These apertures, however, are optional and are suggested merely for use where the location of the renovating apparatus is such that the use of piping 22 and 23, such as indicated, is not feasible.

In FIGURE 1 I have shown the upper end of the chamber 26 closed by screw plug, thus the chamber contributes to the heating of the steamer as well as the heating of the system of coils 11.

While I have illustrated but a single embodiment of the present invention, it will be apparent to those skilled in the art, that various changes, additions, and even omissions may be made in that apparatus without departing from the spirit and scope of the invention as herein described and illustrated.

What I claim is:

1. In garment renovating apparatus including, a base, a casing member mounted on the base and having an open top portion for upwardly delivering processing fluids, permeable garment support means connected to the casing member and extending upwardly therefrom in gas flow communication with the open portion of the casing member; an improved steamer, means connecting said steamer to said permeable garment support means for delivering steam from said steamer into the permeable garment support means, said steamer comprising a body member that forms an open-ended cavity, a steamer block mounted on said body member across the open end of said cavity to form a chamber, said steamer block having a plurality of restricted apertures extending therethrough and being in flow communication with the chamber, means for delivering pressurized steam to said chamber, and means for adding heat to steam flowing through said apertures.

2. In garment renovating apparatus including a base, a casing member mounted on the base and having an open top portion for upwardly delivering processing fluids, permeable garment support means connected to the casing member and extending upwardly therefrom in gas flow communication with the open portion of the casing member; an improved steamer, means connecting said steamer to said permeable garment support means for delivering steam from said steamer into the permeable garment support means, said steamer comprising a body member that forms an open-ended cavity, a steamer block mounted on said body member across the open end of said cavity to form a chamber, said steamer block having a plurality of restricted apertures extending therethrough and being in flow communication with the chamber, said

steamer block also having heating passage means positioned therein, a supply line for providing a supply of pressurized steam, a first branch conduit that is connected to be in fluid communication with said supply line and to said chamber for delivering a portion of said pressurized steam supply to said chamber, and a second branch that is connected to be in flow communication with said supply line and said heating passage means in said steamer block for delivering another portion of said pressurized steam supply to said heating passage means.

3. Apparatus as defined in claim 2 wherein, each of said restricted apertures include a substantially cylindrical reduced area discharge portion.

4. In garment renovating apparatus including a base, a casing member mounted on the base and having an open top portion for upwardly delivering processing fluids, permeable garment support means connected to the casing member and extending upwardly therefrom in gas flow communication with the open portion of the casing member; an improved steamer, means connecting said steamer to said permeable garment support means for delivering steam from said steamer into the permeable garment support means, said steamer comprising a body member that forms an open-ended cavity, a steamer block mounted on said body member across the open end of said cavity to form a chamber, said steamer block having a plurality of restricted apertures extending therethrough and being in flow communication with said chamber, said steamer block also having internal passages positioned therein, a supply line for providing a supply of pressurized steam from an external steam-generating source, a first branch conduit that is connected to be in fluid communication with said supply line for delivering a portion of said pressurized steam supply to said chamber, means operatively associated with said first branch conduit for controlling the delivery of said pressurized steam to said chamber, and a second branch conduit that is connected to be in flow communication with said supply line and said internal passages in said steamer block for delivering another portion of said pressurized steam supply to said internal passages.

5. In garment renovating apparatus including a base, a casing member mounted on the base and having an open top portion for upwardly delivering processing fluids, permeable garment support means connected to the casing member and extending upwardly therefrom in gas flow communication with the open portion of the casing member; an improved steamer, means connecting said steamer to said permeable garment support means for delivering steam from said steamer into the permeable garment support means, said steamer comprising a body member that forms an open-ended cavity, a steamer block mounted on said body member across the open end of said cavity to form a chamber, said steamer block having a plurality of restricted apertures extending therethrough and being in flow communication with said chamber, means for supplying pressurized steam to said chamber, and means in said steamer block for adding heat to steam flowing through said apertures.

6. In garment renovating apparatus including a base, a casing member mounted on the base and having an open top portion for upwardly delivering processing fluids, permeable garment support means operatively con-

nected to the open portion of the casing for receiving garment treating fluids therefrom, conduit means mounted within the casing for heating air therein, and means for creating a flow of heated air upwardly into said permeable garment support means; an improved steamer, means connecting said steamer to said permeable garment support means for delivering steam from said steamer into the permeable garment support means, said steamer comprising a body member that forms an open-ended cavity,

10 a steamer block mounted on said body member across the open end of said cavity to form a chamber, said steamer block having a plurality of restricted apertures extending therethrough and being in flow communication with said chamber, said steamer block also having heating passage means positioned therein, a supply line for providing a supply of pressurized steam, a first branch conduit that is connected to be in flow communication with said supply line for delivering a portion of said supply of pressurized steam to said chamber, a second branch conduit that is connected to be in flow communication with said supply line for delivering another portion of said supply of pressurized steam to said heating passage means in said steamer block, and means for delivering the steam supplied to said heating passage means, subsequently to said 20 air heating conduit means.

7. In garment renovating apparatus including a base, a casing member mounted on the base, and permeable garment support means operatively connected to said casing member; an improved steamer supported by said casing member, said steamer having a body member that forms an open-ended cavity, a steamer block mounted on said body member across the open end of said cavity to form a chamber, said steamer block having a plurality of restricted apertures extending therethrough and being in 30 flow communication with said chamber, means for delivering pressurized steam to said chamber, and means for adding heat to steam flowing through said apertures.

8. In garment renovating apparatus including a base, a casing member mounted on the base, and permeable garment support means operatively connected to said casing member; an improved steamer supported by said casing member, said steamer having means for receiving a supply of pressurized steam, restricted aperture means in flow communication with said receiving means for discharging an expanded high velocity flow of steam, and means for adding heat to steam flowing through said aperture means.
